UNITED STATES PATENT OFFICE.

CHRISTOPHER C. MALTBY, OF CHICO, CALIFORNIA.

WASHER-CUTTER.

SPECIFICATION forming part of Letters Patent No. 268,509, dated December 5, 1882.

Application filed September 2, 1882. (No model.)

To all whom it may concern:

Be it known that I, C. C. MALTBY, of Chico, county of Butte, State of California, have invented an Improved Washer-Cutter; and I hereby declare the following to be a full, clear, and exact description thereof.

My invention relates to an improved washer-cutter; and it consists in a novel arrangement and construction of the stock, spring-center cutting-arms, and set-screw, as will herein-after be fully set forth in the description, and particularly pointed out in the claim.

The object of my invention is to provide a washer-cutter easy of adjustment and effective in operation.

Referring to the accompanying drawings, Figure 1 is a perspective view. Fig. 2 is a vertical section.

A represents a stock having in its lower end the pivot-center B. This center is here shown as having two tines, b, adapting it to secure a better hold, though it may have more than two with like effect. The upper end of the center B has a circumferential groove, e, in which the point of a catch, a, pivoted to the stock, is adapted to fit, whereby the stock is secured upon the center, though adapted to turn thereon. The stock A near its upper end is slotted and receives the radial arms D D', passing through one above the other, and fitted together by tongue and groove, whereby each arm may have a movement independent of the other, though both may be moved together when desired. The arms D D' turn downwardly at right angles, the upper arm, D, being outside and the lower arm, D', inside. They are provided with slender knives d d', which cut out the washer.

Inside the stock, and secured to the upper end of the center B, is a spiral spring, e, through which and into a socket in the said center fits a pin, m, having a large head, whereby it is hung upon and effects the spring e. The head of this pin impinges against the lower arm, D', and thus, when the catch a is raised and the center pressed against the board, the stock may be pressed down, compressing the spring e, which throws it up again when the pressure is relieved.

E is a set-screw fitted in the top of the stock. Its lower end impinges against the upper arm, D, and secures both radial arms at any desired point in the stock.

The operation of the cutter is as follows:

The pivot-center B is first forced into the leather or other material from which the washer is to be cut and into the bed-board upon which the material lies. The double tine of the center gives it a firm hold and prevents any tendency to turn. If I am about to cut out an annular washer, there are two things to be determined. The first is the diameter, of the washer and the second is its width. Knowing these, I loosen screw E and move out the arm D to the radius desired to get the diameter and then move the arm D' toward the arm D to get the desired width. Then by setting the screw E down both arms are secured in this position. The thumb being then pressed upon the catch a, releasing it from the groove e, the stock A is pressed down upon the center B until the knives d d' are brought in contact with the material, when by revolving the stock the knives cut out the washer. When finished and the pressure relieved the stock and knives are moved up by the spring e, and the catch a, returning to the groove e, secures them up out of the way.

In order to insure accuracy in the adjustment of the radial arms, I make on the upper arm, D, a scale denoting in inches and fractions thereof the radius of the washer, and a scale on the lower-arm, D', denoting the width of the washer. These are shown in Fig. 1, and by them the device may be accurately adjusted.

I am aware that washer-cutters are known in which a revolving stock having a radial arm carrying separately-adjustable cutting-knives is used, and therefore I do not claim such a device, broadly; but

What I do claim as new, and desire to secure by Letters Patent, is—

The slotted stock A, having a pivoted catch, a, and the spring pivot-center B, having a groove, e, in which the catch a fits, and tines b, as shown, in combination with the adjustable bent radial arms D D', passing through the slotted stock, and having cutting-knives d d', and the set-screw E in the top of the stock, all arranged as shown, and substantially as herein described.

In witness whereof I hereto set my hand.

CHRISTOPHER C. MALTBY.
